UNITED STATES PATENT OFFICE.

GEORGE F. CHAPPELL, OF NEW YORK, N. Y.

HANDLE FOR PILL-CUTTERS.

SPECIFICATION forming part of Letters Patent No. 242,883, dated June 14, 1881.

Application filed March 16, 1881. (No model.)

To all whom it may concern:

Be it known that I, GEORGE F. CHAPPELL, of the city, county, and State of New York, have invented a new and Improved Handle for Pill-Cutters; and I do hereby declare the following to be a full, clear, and exact description of the same, reference being had to the drawings accompanying and forming part of this specification.

10 The handles in use before my invention were composed of a corrugated pill-cutting plate in combination with a wooden slab. The mass of material, in a thoroughly-mixed state, out of which the pills are made, was first rolled down 15 on a ground-glass slab to a roll of the required diameter of the pills to be cut from it by the wooden slab or back of the handle. Then the handle was reversed and its corrugated side passed back and forth several times over this 20 roll in a direction at right angles to its length, in order to cut the roll and to shape in pills the cut portions, from which last operation there results the finished pills.

In the table in front of the ground-glass slab 25 over which the handle is passed in the first operation above described is placed a corrugated plate, and onto which the roll rolled up on this ground-glass slab is pushed in the second operation above described, the edges of which in 30 this second operation must coincide with the edges in the corrugated plate of the handle; otherwise the pills will be imperfectly formed.

Sometimes out of material for one hundred thousand pills is produced but ninety thousand, thus entailing a loss on the manufacturer 35 and the giving of imperfect doses of medicines to the consumer. This, in cases of subtle poisons, which are sometimes worked up into very small pills, is so objectionable that the pills have 40 to be tested and frequently remade. In large pills it is sometimes, by reason of irregularity in their size, necessary to reassort them, selecting out the irregular and too light or too heavy ones in order to remake them. This imperfection in the pills is sometimes occasioned 45 by reason of the springing of the wooden slab at its center when the pill material does not yield readily to the operation of rolling it into the long roll preparatory to the cutting and 50 shaping operation, but more frequently by reason of the wooden slab becoming warped.

So sensitive to any change of direction are the corrugated edges on the metallic plate contained on the handle that a divergence of the thickness of tissue or thin writing-paper will 55 affect unfavorably the operation of pill-making. This warping is caused by the changes in the weather, also by the frequent washing of the slabs, which washing they are subjected to after the operation of pill-making in order to clean 60 them for future operations. This necessitates constant attention to the handles, such as making true their backs and taking the warp or deflection out of the plates. A thin plate of metal has been tried on the wooden back as a sheathing; but the wood warps it. If made heavy 65 enough to prevent warping, there is an objection to it on account of its adding too much weight to the handle. If too much weight is added to the handle, it becomes objectionable to the operatives, most of whom are women and girls, and the dealers will not have them.

My improvements consist in combining, with the corrugated pill-cutting plate, the handle of a ribbed metal plate, so that the deflecting 75 in use of the handle and its warping when not in use will be overcome, and at same time the handle, although wholly composed of metal, will be rendered light in handling in the operation of forming pills.

In the drawings is represented a handle for pill-cutting machines, in which handle is embodied my said improvement.

Figure 1 is a plan view of the handle with the corrugated cutting-plate shown partly broken 85 away, and Fig. 2 is a cross vertical section taken through the line *x x* of Fig. 1.

a is the corrugated pill-cutting plate. At its back is a light metal plate, *b*, containing strengthening-ribs *c c c c*, &c. At the ends of this last-named plate are two knobs or projections, *d d*, by means of which the pill-handle is manipulated by the operator.

e e are the end plates, one on each end of the plate *b*, and which gage on the table of the pill-machine the thickness or diameter of the pills in the process of their formation, first in the long roll with the back of the plate *b* of the pill-handle, and, secondly, in its completion in the corrugations on the pill-handle and on the table of the machine. These plates, through which the knobs or projections *d d* also pass, are at 95 100

tached to the plate *b* by means of screws *f f f f*. The corrugated plate *a* is attached to the plate *b* at each of the four corners by means of screws *g g g g*. This gives a handle which will not, under any circumstances, with ordinary wear and tear, get out of order, and which can be operated with by the most delicate operator without difficulty.

I claim—

10 As an improved article of manufacture, the handle for pill-cutters herein described, consisting of the corrugated face-plate *a* and the

metallic flanged back plate, *b*, having the series of ribs *c c*, the projecting end handles, *d d*, and the projecting gage-plates *e e*, attached to the ends of the back plate, the back plate and face-plate being connected by screws or pins passing into the ribs *c*, all substantially as set forth.

GEORGE F. CHAPPELL.
